ORTHOPEDIC CHILD'S SANDAL

Ernest H. Bettmann, New York, N. Y., assignor to
Walter Liebrecht, New York, N. Y.

Application June 6, 1945, Serial No. 597,868

10 Claims.

The present invention is directed to orthopedic devices, more particularly to a sandal adapted for use by infants at the time they are learning to walk. It also can be worn by older children and grown-ups, eventually also in shoe form.

Generally the normal infant has feet which are perfectly normal, with the bones, joints and muscles in proper relationship. After it learns to walk, various difficulties arise in that the original weight bearing changes and normal relation of bones and muscles of the feet often lead to irreparable deformities and abnormal posture which not only interfere with the normal use of the feet, but also cause muscle and joint pain. Sometimes the deformities so developed may be alleviated and often completely corrected by exercises, appliances and other means. However, such treatment is long drawn out and expensive and very often burdensome to the patient.

The present invention is intended and adapted to overcome the difficulties set forth above and to provide means for proper foot muscle function and preventing bone deformities and also for correcting such deformities after they have arisen.

It is also among the objects of the present invention to provide a device which may be worn in the normal manner by an infant learning to walk, whereby the muscles of the foot are strengthened during this period and the bone structure is retained in its normal position.

It is still further among the objects of the present invention to provide a device which may be worn by the infant or older individuals, whereby deformities either naturally occurring or developed later may be corrected.

In practicing the present invention there is provided a sandal having a flat bottom and being open at the front and sides. This gives free play to the muscles of the foot. At the rear there is provided a back portion which embraces the heel and serves to keep the sandal in proper relationship to the foot. The under side of the sandal bottom is provided with a roughened surface so as to provide sufficient friction in order to give a firm hold on the surface of the ground and not allow slippage during walking. The upper side of the sandal bottom is provided with an irregular surface, usually in the form of bristles, knobs, rolls, tubes or the like, preferably resilient in character, forming a soft, rough walking surface. This serves as a physiological stimulus for the muscles of the soles of the foot and increases circulation therein, thus providing

(Cl. 36—8.5)

proper development in the muscles of the foot which are used in walking.

There is also provided a scaphoid pad at the middle side of the sandal bottom to properly maintain the scaphoid in the vault structure, being the weak spot in relationship with the rest of the foot structure. There is also provided a pronator wedge at the front of the sandal tending to hold in normal position the metatarsal heads and fore foot. The sandal projects a substantial distance beyond the pronator wedge and allows the toes to flex downwardly and thus the muscles of the toes are strengthened and develop their grasping power while the infant is learning to walk. At the heel portion there is a supinator wedge on the middle side thereof.

The combination of these elements gives freedom of action of all the foot muscles during walking, while at the same time providing means for directing the muscles and the bones into their final relative positions and the strengthening of the muscles retains the bone structure properly and results in the formation of normal arches.

In the accompanying drawing constituting a part hereof and in which like reference characters indicate like parts,

Fig. 1 is a side elevational view of a sandal made in accordance with the present invention, some parts being broken away for clearness;

Fig. 2 is a view of the under side of the sandal bottom member;

Fig. 3 is a top plan view of the sandal;

Fig. 4 is a top plan view of a modified form of sandal, showing particularly a simple means for elevating the wedge structures;

Fig. 5 is a vertical cross-sectional view taken along the line 5—5 of Fig. 1, illustrating a means for raising the wedges; and

Fig. 6 is a vertical cross-sectional view taken along the line 6—6 of Fig. 4, showing an alternate means for accomplishing the same result.

The sandal consists essentially of a flat bottom member 1 of substantially uniform thickness, having corrugations 2 preferably diagonally placed on the bottom thereof. The upper surface of member 1 is provided with soft rubber or other projections 3, which as shown are in the nature of short bristles. A back 4 is attached to the rear portion of member 1 and is intended to embrace the heel. A pair of straps 5 and 6, with a cross connecting strap 7 are secured to the bottom 1 and a strap and buckle 8 is also provided whereby the sandal may be attached to the foot.

Along the medial side 9 of the sandal there is

provided a scaphoid pad 10 just forward of the back. A supinator wedge 11 is placed on the heel portion of bottom 1 with its high point 12 along the medial side and its front 13 being practically adjacent to pad 10. Wedge 11 extends to point 14 practically at the lateral side of the sandal and gradually decreases in thickness until it merges at 14 with bottom 1. There is a direct connection at 14 which is in the nature of a hinge about which wedge 11 may be moved.

Along the lateral side is a triangular wedge 16 having its highest area along the line 17 at the front of the wedge. The forepart 18 of the sandal extends a sufficient distance beyond line 17 to provide a place for the toes of the wearer. Wedge 16 gradually decreases in thickness from the high area at 17 to the line along which it merges with the bottom 1, said merger forming a hinge about which the wedge 16 may be moved. The medial point 19 of wedge 16 terminates at the medial sides 9 and the rearmost point 19' terminates a substantial distance in front of wedge 11 of the sandal.

In order to adjust the height of one or both of wedges 11 and 16, there is provided a screw member having a thumb head 20 passing through a similarly threaded member 21 which is secured to bottom 1. A screw is attached to an inclined plane 22 underneath wedges 11 and 16. Manipulation of head 20 will raise or lower the wedges, as can be readily seen from Fig. 5.

In the modification shown in Fig. 4, there is provided a strap 23 placed diagonally of the sandal, the front end 24 thereof being secured to the under side of wedge 16 as more particularly shown in Fig. 6. The rear end 25 of the strap is similarly attached to the under side of area 12 of wedge 11. The foot of the wearer passes underneath strap 23 and strap 26 and buckle 27 provides means for holding the sandal on the foot of the wearer. In this form the act of walking will cause a slight upward pressure on strap 23, tending to raise wedges 11 and 16 and thus tending to hold the bones of the foot in their proper relative positions.

Although the invention has been described setting forth two specific embodiments thereof, it will be apparent to those skilled in the art that various modifications may be made therein within the spirit of the invention. For instance, the material of which the several elements are made may be any of those commonly known and used in the shoe industry. The bottom 1 may be made of plastic or elastic material, rubber and the like, and corrugations and bristles may be intricately formed therein in a molding operation. Wedges 11 and 16 may be provided with means other than those described for raising and lowering the same, such as springs, or such means may be omitted and adjustments if desired may be made in other ways.

The principal features of the invention may be incorporated in a shoe, which would have a double sole, the inner being made as set forth herein. It would have the heel supination wedge, the fore foot pronation wedge, holes in the inner sole, to provide proper foot respiration, and a stirrup-like leather band replacing the scaphoid pad and anchored to the medial side of the shoe.

These and other changes in the details of construction may be made in the spirit of the invention, the scope of which is defined by the claims appended hereto.

I claim:

1. A sandal comprising a flat bottom member open at the sides and front and having a back portion to embrace the heel, a scaphoid pad at the medial side of said member, a forefoot pronator wedge thereon for the metatarsal heads, and a heel supinator wedge at the medial side thereof, the fore part of said member extending beyond said pronation wedge.

10 2. A sandal comprising a flat bottom member open at the sides and front and having a back portion to embrace the heel, a roughened friction surface on the under side of said member, a scaphoid pad at the medial side of said member, a forefoot pronator wedge thereon for the metatarsal heads, and a heel supinator wedge at the medial side thereof, the fore part of said member extending beyond said pronation wedge.

15 3. A sandal comprising a flat bottom member open at the sides and front and having a back portion to embrace the heel, a resilient irregular surface on the upper side of said member, a scaphoid pad at the medial side of said member, a forefoot pronator wedge thereon for the metatarsal heads, and a heel supinator wedge at the medial side thereof, the fore part of said member extending beyond said pronation wedge.

20 4. A sandal comprising a flat bottom member open at the sides and front and having a back portion to embrace the heel, a scaphoid pad at the medial side of said member, a forefoot pronator wedge thereon for the metatarsal heads, said wedge being hinged to said member and means for varying the height of said wedge, and a heel supinator wedge at the medial side thereof, the fore part of said member extending beyond said pronation wedge.

25 5. A sandal comprising a flat bottom member open at the sides and front and having a back portion to embrace the heel, a scaphoid pad at the medial side of said member, a forefoot pronator wedge thereon for the metatarsal heads, said wedge being hinged to said member and means for varying the height of said wedge including a screw and inclined plane arrangement and a heel supinator wedge at the medial side thereof, the fore part of said member extending beyond said pronation wedge.

30 6. A sandal comprising a flat bottom member open at the sides and front and having a back portion to embrace the heel, a scaphoid pad at the medial side of said member, a forefoot pronator wedge thereon for the metatarsal heads, and a heel supinator wedge at the medial side thereof, said supinator wedge being hinged to said member and means for varying the height of said wedge, the fore part of said member extending beyond said pronation wedge.

35 7. A sandal comprising a flat bottom member open at the sides and front and having a back portion to embrace the heel, a scaphoid pad at the medial side of said member, a forefoot pronator wedge thereon for the metatarsal heads, and a heel supinator wedge at the medial side thereof, the fore part of said member extending beyond said pronation wedge, and a strap having its ends attached to said wedges and adapted to pass over the foot of the wearer, said wedges being hinged to said member.

40 8. A sandal comprising a flat bottom member open at the sides and front and having a back portion to embrace the heel, a scaphoid pad at the medial side of said member, a forefoot pronator wedge thereon for the metatarsal heads, and a heel supinator wedge at the medial side thereof, the fore part of said member extending

beyond said pronation wedge, said pronator wedge being triangular in outline and being highest at said heads, tapering to meet said member in front of said back portion and part way across said member.

9. A sandal comprising a flat bottom member open at the sides and front and having a back portion to embrace the heel, a scaphoid pad at the medial side of said member, a forefoot pronator wedge thereon for the metatarsal heads, and a heel supinator wedge at the medial side thereof, the fore part of said member extending beyond said pronation wedge, said pad being sub-

stantially contiguous with the fore part of said supinator wedge.

10. A sandal comprising a flat bottom member open at the sides and front and having a back portion to embrace the heel, a scaphoid pad at the medial side of said member, a forefoot pronator wedge thereon for the metatarsal heads, and a heel supinator wedge at the medial side thereof, the fore part of said member extending beyond said pronation wedge, said supinator wedge merging with said member at the lateral side thereof.
